LEATHER BELT BUCKLE

Martin Greenblatt, Bronx, N. Y.

Application February 19, 1942, Serial No. 431,461

11 Claims. (Cl. 24—163)

This invention relates to new and useful improvements in a leather belt buckle.

More specifically, the invention proposes the construction of a belt buckle entirely of leather and characterized by a base frame section having a centrally located transverse wall portion upon one face of which a locking tongue is supported and a top frame section mounted upon and around the edge portions of the bottom frame section in a manner to form a recess within which the attached tongue is disposed.

Heretofore it has been common practice to form a belt buckle of this type of a single piece of leather material in which one face of the centrally located transverse wall portion was cut away forming the recessed area for the locking tongue. This invention proposes improving upon this prior method of constructing a leather belt buckle by forming the buckle of two pieces of leather eliminating the costly cutting away step permitting the belt buckle to be formed of cheaper thinner leather without sacrificing any of the usefulness present in the prior art constructions.

A further object of this invention proposes several different methods for attaching the frame sections together in a manner to form an integral unit of them.

It is a further object of this invention to provide means for securely attaching the adjacent ends of the locking tongue and belt strap to the face of the centrally located transverse wall in a manner to permit the free end of the belt strap to be engaged with the free end of the locking tongue to form a continuous loop of the belt strap.

Another object of this invention proposes the provision of a means upon one of the frame sections for shortening the operative length of the locking tongue in a manner to stiffen the same and prevent the tongue from accidentally becoming disengaged from the strap.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a belt having a leather buckle constructed in accordance with this invention.

Fig. 2 is a vertical sectional view taken on the line 2—2 of Fig. 1.

Fig. 3 is a vertical sectional view taken on the line 3—3 of Fig. 2.

Fig. 4 is a perspective view of the base frame section per se.

Fig. 5 is a perspective view of the top frame section per se.

Fig. 6 is a perspective view of the locking tongue per se.

Fig. 7 is a plan view of a belt buckle constructed in accordance with a modification of this invention.

Fig. 8 is a longitudinal vertical sectional view taken on the line 8—8 of Fig. 7.

Fig. 9 is a plan view of a belt buckle constructed in accordance with another modification of this invention.

Fig. 10 is a transverse vertical sectional view taken on the line 10—10 of Fig. 9.

Fig. 11 is a plan view of a belt buckle constructed in accordance with still another modification of this invention.

Fig. 12 is a transverse vertical sectional view taken on the line 12—12 of Fig. 11.

Fig. 13 is a longitudinal vertical sectional view taken on the line 13—13 of Fig. 11.

Fig. 14 is a perspective view of the slide per se.

Fig. 15 is still another plan view of a belt buckle of a slightly different shape.

The leather belt buckle, according to this invention, includes a leather base frame section 10 substantially of diamond shape. This base frame section 10 is cut to have a centrally located transverse wall on opposite sides of which openings 12 and 13 are located.

A top frame section 14 of leather is mounted upon and around the edge portions of the bottom frame section 10. The top frame section 14 is also substantially of diamond shape. A suitable mucilage 15 is applied to the adjacent faces of the frame sections 10 and 14 for securing them together as a unit.

A locking tongue 16 of leather has one of its ends secured to the top face of the transverse wall 11 adjacent the opening 13. This attachment is accomplished by engaging a rivet 17 through the end of the tongue 16 and the transverse wall 11. The free end of the locking tongue 16 is projected across the opening 13 and rests upon the top face of the top frame section 14.

A strap 18 also of leather is attached to the belt buckle. This strap 18 has one of its ends projected upwards through the opening 12 to engage over the top face of the transverse wall 11 and the attached end of the locking tongue 16. Mucilage 19 securely attaches the end of the strap 18 to the transverse wall 11 of the belt buckle.

The free end of the strap 18 is provided with a

plurality of openings 20 and is adapted to be projected upwards through the opening 13 to have one of its openings 20 engaged by the free end of the locking tongue.

In the form of the invention disclosed in Figs. 7 and 8, the construction of the leather belt buckle is similar to that previously described, differing merely in the manner of securing the frame sections together as a unit and in the manner of securing the end of the strap 18 to the top face of the wall portion 11.

The frame sections 10 and 14 are secured together as a unit by means of a line of stitches 15'. The free end of the strap 18 is secured to the top face of the transverse wall portion 11 by means of a line of stitches 19'.

In Figs. 9 and 10 still another means is shown for attaching together the frame sections 10 and 14 and for securing the end of the strap 18 to the face of the transverse wall portion 11.

In this form of the invention a strip of binding material 15'' is engaged about the edge portions of the frame sections 10 and 14 and is secured in position by mucilage material 21. The binding material 15'' comprises a strip of leather, fabric, or cellulose substance. The end of the strap 18 is secured in position by means of a plurality of rivets 19''.

In the form of the invention disclosed in Figs. 11 to 14 a leather buckle similar in construction to that shown in Fig. 7 is provided with a means for stiffening the free end of the locking tongue 16 to prevent it from becoming accidentally disengaged from the end of the strap 18. This means comprises a slide 22 constructed of metal and substantially of U-shape. The arms 23 of the slide 22 slidably engage grooves 24 formed in the sides of the top frame section 14. The intermediate arm of the slide 22 is formed to have spaced superimposed layers 25 through which the free end of the tongue 16 is engaged.

In using this form of the invention the free end of the locking tongue is passed through one of the openings in the free end of the strap 18 and the slide 22 is moved forward to the position illustrated in full lines in Fig. 11 to shorten the flexing length of the tongue 16 and so prevent the tongue from becoming disengaged from the end of the strap 18. To again free the tongue to permit the tongue to be disengaged from the opening in the end of the strap 18, the slide is moved back to the position illustrated by the dot and dash lines 22' in Fig. 11.

In Fig. 15 a leather belt buckle is illustrated in which the frame sections 10' and 14' are substantially rectangular in shape. In other respects this form of the invention is similar to that disclosed Figs. 1 to 6 and like reference numerals are used to designate like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a leather belt buckle having a leather locking tongue for engaging the strap of a belt, a leather base frame section having a centrally located transverse wall portion for supporting said leather tongue, a leather top frame section

mounted upon and around the edge portions of said base frame section, and means securing said frame sections together as a unit.

2. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, said frame sections being substantially diamond shaped.

3. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, said frame sections being rectangular in shape.

4. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, comprising mucilage applied between the adjacent faces of said frame sections.

5. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, comprising stitches engaged through the superimposed portions of said frame section.

6. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, comprising binding material engaged about the superimposed edge portions of said frame sections, and mucilage securing said binding strip in position.

7. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, comprising binding material engaged about the superimposed edge portions of said frame sections, and mucilage securing said binding strip in position, said binding material, comprising a piece of leather, fabric or cellulose material.

8. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, said lock-

ing tongue having one of its ends riveted to said transverse wall.

9. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, and means securing the end of said strap in position upon the face of said transverse wall portion.

10. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, and means upon one of said frame sections engaging the free

end of said locking tongue for stiffening said tongue to maintain its engaged position with said strap.

11. In a leather belt buckle having a leather locking tongue for engaging the strap of a belt, a leather base frame section having a centrally located transverse wall portion for supporting said leather tongue, a leather top frame section mounted upon and around the edge portions of said base frame section, and means securing said frame sections together as a unit, and means upon one of said frame sections engaging the free end of said locking tongue for stiffening said tongue to maintain its engaged position with said strap, comprising a U-shaped slide having its side arms engaging grooves formed in its respective frame section, and an intermediate wall of spaced superimposed layers through which the free end of said locking tongue is projected.

MARTIN GREENBLATT.
